HOLDER FOR STROPPING RAZOR BLADES

Louis E. Hansen, Toronto, Ontario, Canada

Application May 15, 1944, Serial No. 535,603

6 Claims. (Cl. 30—332)

The invention relates to certain new and useful improvements in holders of the class in which a safety razor blade of the double edge type is held for sharpening as by a strop.

The invention particularly appertains to a holder of the character in which a razor blade is placed between two plates in a manner to expose an edge portion to be sharpened. One of the plates has a handle, and the other is detachably connected by means including a collar which is so devised as to bring about a locking engagement by an axial movement relative to said handle, whereby the blade is securely clamped in place.

The aim of the present invention is to provide an improved form of securing means for the detachable plate, which is highly efficient in operation and can be manipulated quickly and easily without having to slide or shift the collar axially along the handle.

A further object of the invention is to provide a holder which is cheap to manufacture, and one in which the component parts may be mouldably produced of a plastic material.

The invention comprehends a holder in which the means for locking the plates in clamping engagement about a blade comprise a detachable connection at the outer ends of the plates and a collar having a cam end face in spiral form extending from a slotted portion for engaging a shoulder on a shank which is inserted in the slot so that upon turning the collar the plates will be urged to clamp an interposed blade.

The collar is turnably mounted on the handle that extends from one of the plates and engages the adjacent end face thereof. The shank extends from the other plate and the shoulder thereon is formed by a radially disposed nodule.

The invention is illustrated in the accompanying drawing in which like numerals of reference denote corresponding parts in each of the several figures.

In the drawing, Fig. 1 is a perspective view of the bottom plate which is supplied with a handle on which the collar is disposed. In this view the collar is removed from its true position next to the plate in order to show the cut-away portion of the handle on which it loosely fits.

Fig. 2 is a similar aspect of the top plate.

Fig. 3 is a perspective view of the assembled holder with a blade clamped therein.

Fig. 4 is a longitudinal section of Fig. 3.

Fig. 5 is an end view of the collar.

Fig. 6 is a sectional aspect of the collar taken on line 6—6 of Fig. 5.

Now, in the selected embodiment herein delineated it will be seen that the bottom plate 10 and the top plate 11 are of well known shape and taper in cross section to a common side from which a razor blade 12 protrudes when held thereby so that the exposed edge may contact a strop in the sharpening operation. The usual locating ridge 13 upstands from the bottom plate for fitting into the apertured blade so as to properly position it. The ridge registers with a slot 14 in the top plate, and in the present instance is made much shorter than said slot to permit the top plate to slide endwise for the purpose of its attachment and removal as will later more clearly appear.

The handle 15 is a unitary part of the bottom plate and is desirably of round shape in cross section. The portion immediately adjacent the plate juncture is cut away as at 16 equable with the proper surface of the bottom plate for a length slightly in excess of the length of a collar 17 which loosely encircles the same. The collar abuts the inner face 10' of the bottom plate and is free to turn on the handle. The portion of the handle which is cut away is less than half of the diameter thereof and the segmental space thus provided is encircled by the collar.

The collar is supplied with a slot 18 running lengthwise and open to the ends thereof. The bore of the collar is enlarged at its outer end to provide a counterbore having a thin wall 19 and an inner radial face 20 which is fashioned as a helical cam surface, as will be best seen from an inspection of Figs. 4 and 6.

The top plate 11 is supplied at its inner end with an integral shank or member 21 which in section is a segment of a circle complementary to the part 16 of the handle which is reduced. The shank 21 is of a fit to slide freely in the collar and has at its outer end an integral tit or nodule 22 projecting radially of its circular top surface. The tit or nodule fits into the counterbore and is adapted to be engaged by the cam surface when the collar is turned. The cam surface urges the tit or nodule axially in the direction of the outer end of the handle and thus draws the top plate into abutting engagement with the inner end of the collar to compose a secure locking connection.

The outer ends of the plate 10 and 11 are detachably connected as by the provision of a slot 23, which extends inwardly of the outer edge of the plate 10, and a downwardly curved clip or hook 24 which fits into the slot 23 and engages the edge 25 thereof to co-act with the collar in detachably clamping the top plate.

By this construction it will be manifest that in the use of the holder a blade is first placed on the bottom plate and then the top plate is placed thereover and the shank 21 is inserted in the collar which has its slot 18 aligned with the slot 22. As the shank slips into place the hook 24 engages the slot 23. When the collar is turned the hook firmly engages slot 23 as the top plate is drawn towards the handle by the cam of the collar. The blade is thus firmly clamped and when sharpened can be quickly removed by a reverse movement of the collar.

What I claim is:

1. A holder of the class described comprising a bottom plate and a top plate between which a razor blade is interposed for stropping of an edge exposed thereby, and means for detachably connecting adjacent ends of said plates to clamp the interposed blade, said means at one end of said plates including a member projecting from the edge portion of said bottom plate and being of a circular cross section intercepted by a flat face at the inner surface of the bottom plate, a collar sleeved on said member for turning movement and limited against inward axial movement, said collar having a lengthwise slot and having a radial face spirally formed to provide a cam at the outer end thereof, a shank projecting from the edge portion of said top plate and being a

cross section complementary to said member for insertion in said collar inwardly of the slot thereof, and a nodule carried by said shank for engaging said cam after it has been passed through said slot in the insertion of said shank.

2. A holder as claimed in claim 1, in which the said member projecting from the edge portion of said bottom plate constitutes a handle.

3. A holder as claimed in claim 1, in which the said member projecting from the edge portion of said bottom plate constitutes a handle which is round in cross section and cut away at its inner end to provide the flat face referred to, that is at the inner surface of said bottom plate.

4. A holder as claimed in claim 1, in which said collar is shouldered against the said edge portion of said bottom plate to preclude inward axial movement.

5. A holder as claimed in claim 1, in which said cam is formed within a counterbore and is operative to secure the top plate with a clamping effect.

6. A holder as claimed in claim 1, in which the means at the other end of said plates for detachably connecting adjacent ends thereof comprise a slot provided in the bottom plate, and a hook fashioned on the top plate and adapted to have firm locking engagement with this slot.

LOUIS E. HANSEN.
